UNITED STATES PATENT OFFICE

2,590,335

SELECTIVE KEYBOARD CLEARING MEANS

James A. Maffie, Belleville, N. J., assignor to
 Monroe Calculating Machine Company, Orange,
 N. J., a corporation of Delaware

Application March 12, 1949, Serial No. 81,144

4 Claims. (Cl. 235—130)

1

The invention relates to keyboard clearing means for motor operated calculating machines having means for rendering the operation of the clearing means ineffective to release keys of any selected columns, thereby providing a constant setting for the entered value.

It is the purpose of this invention to provide means selectively operable under control of an operation key, such as a clear key, which will permit a constant factor setting in the keyboard of a motor operated machine.

The keyboard comprises a plurality of columns of depressible value keys; each of said columns including digital value keys and a zero key. Each of the columns is provided with a spring urged latching bail for holding the keys in depressed position and the movement of any key toward depressed position is adapted to move said bail to release any set key, including the zero key, in the related column prior to the latching action of said bail for the key being depressed.

The clearout means includes a bail adapted to simultaneously depress all of the zero keys thereby releasing any set digital value keys and latching the zero keys in depressed position. If the bail is held in operated position by holding the zero key or clearout key depressed while setting a new value into the keyboard, the zero keys in the related columns will not be released, and subsequent operation of the bail will therefore be ineffective to clear the new value from the keyboard. Such an arrangement is fully disclosed in United States Patent No. 1,750,565, issued to E. F. Britten, Jr., on March 11, 1930. According to said disclosure, the clearout bail is manually operated by appropriate linkage upon depression of a clear key. To provide for a constant value setting, the clearout bail may be held in operated position by holding the clear key manually depressed.

A machine having motor operated keyboard clearout means of substantially the same character as the manually operated means disclosed in the above noted Patent No. 1,750,565 is fully disclosed in the copending application of Herman Gang, Serial No. 8,547, filed February 16, 1948, now Patent No. 2,531,206, issued November 21, 1950. According to said disclosure, the clearout bail is driven by a single cycle clutch to its operated position and then released; a suitable spring being provided to restore and maintain the bail in normal position. Holding the operating key, which controls engagement of the clutch, in depressed position will not hold the clearout bail in operated position as the clutch is limited to a

2

single cycle of operation to rock and release the bail. The present invention provides means selectively controlled by manipulation of the operating key to hold the bail in operated position thereby permitting a constant factor setting in the keyboard.

The invention, however, will best be understood from the following description with reference to the accompanying drawings in which:

Fig. 1 is a right side view of the machine with parts in section showing the latching means for the clearout bail, the operating key and portions of the linkage for driving the clearout bail.

Fig. 2 is a detailed view showing the latching means engaging and holding the clearout bail in operated position.

Fig. 3 is a detailed view of the key stem construction for the digital value and zero keys and the latching bail therefor.

Fig. 4 is a partial section taken substantially on the lines 4—4 of Fig. 1, showing the clearout bail, the lower ends of the zero key stems, portions of the driving means and controls therefor.

Fig. 5 is a fragmentary side elevation of the clearout clutch, controls therefor and the reciprocating means driven by the clutch.

Keyboard clearing means

The digital value keys 18 (Figs. 1 and 3) are adapted upon depression to adjust selector bails 20 to set the selected values in digital actuators 5. The first keys 19 of each column represent zero value and have no adjusting function in connection with the selector bails 20. Each column of keys 18, 19 is provided with a bail 432 for latching any key in the related column in depressed position by engagement with a notch (Fig. 3) with which each key stem is provided. The stems of the keys 18, 19 are of well known construction in which each is provided with a cam edge which, upon depression of the key, is adapted to move the related bail 432, thereby releasing any set key in that column. The zero keys 19 are therefore, in effect, columnar releasing means. Accordingly, provision is made to simultaneously depress the rows of zero keys 19 extending across the front of the keyboard, thereby releasing any set digital value keys.

The stem of each of the zero keys 19 (Figs. 1 and 4) terminates at its lower end in a horizontally disposed portion. Extending across the machine is a bail 515 pivotally mounted on a shaft 516. The rearward edge of bail 515 overlies the horizontal ends of the zero key stems and is in contact therewith when the keys are in released

position. Thus, it will be seen that when bail 515 is rocked clockwise (Figs. 1 and 2) (by means to be described) the zero keys 19 will be depressed, thereby releasing the value keys 18 which may be set in each column and latching the zero keys by means of bails 432.

Driving means for the clearing operation

The driving means for the clearing operation comprises a one cycle clutch 464 (Fig. 5) mounted on the left hand side frame of the machine and driven by the motor through suitable gearing. As disclosed in the aforementioned copending application, Serial No. 8,547, clutch 464 may be engaged upon depression of any one of a plurality of operating keys; which keys also serve to select the particular clearout operation to be performed. The present disclosure concerns the keyboard clearing operation only and the selection of this operation and the engagement of clutch 464 is effected upon depression of an operating key 466 (Fig. 1).

The stem of key 466 is attached at its lower end to the forward end of a lever 470 which is pivotally mounted at its rear on a stud 472 fixed on the right hand side frame. Lever 470 is provided with a depending arm which terminates in a horizontally disposed finger 470' which is adapted for contact with an arm of bell crank 474 (Figs. 1 and 4). Bell crank 474 is pivotally mounted on a vertical shaft 476 suitably fixed and depending from a cutout section of the right hand side frame. The other arm of bell crank 474 is pivoted to a slide 478 which extends across the machine and therefore depression of key 466 will move said slide toward the left of the machine. This movement of slide 478 will release a latch 482 (Figs. 4 and 5) which allows clutch 464 to be engaged and effect the driving connection to bail 515.

The latch 482 (Figs. 4 and 5) which is normally in engagement with a shoulder 480' of a slide 480 holds said slide in its rearward position against the tension of a spring 481. Slide 480 is slidably supported at its forward end on a shaft 484 projecting externally of the left hand side frame and extending across the machine, and at its rearward end said slide is attached to an arm 485 fixed on a shaft 486 rotatably mounted in the side frame. The leftmost end of slide 478 is in abutment with an upstanding ear 482' of latch 482. Thus, movement of slide 478 toward the left will rock latch 482 clockwise against the tension of spring 483, releasing slide 480 which will be pulled forward by spring 481. The left hand end of slide 478 is provided with a recess and when the slide is moved to active position the forward end of released slide 480 will enter said recess and hold slide 478 in set position until the engaging end of slide 480 has been removed when said slide is restored to latched position.

Clutch 464 (Fig. 5) is driven by a suitable gear train from the motor and is of well-known construction in which a spring pawl mounted on the driven member of the clutch is held out of engagement with the driving member by a detent. For this purpose a detent 487 is fixed on shaft 486 and when the slide 480 is released, shaft 486 through arm 485 will be rocked counterclockwise thus removing detent 487 from engagement with the pawl of clutch 464, thereby engaging the drive to the motor. Upon engagement of clutch 464, the circuit breaker for the electric motor must be closed. For this purpose, a bell crank 490 pivotally mounted on the frame is urged counterclock-

wise (Fig. 5) by a suitable spring. A horizontally disposed arm of bell crank 490 is in contact with a pin on the forward end of lever 200 and said bell crank is restrained from rotation by a lug 491 on the slide 480 in blocking contact with a depending arm of said bell crank. When slide 480 moves forwardly, bell crank 490 will be urged counterclockwise by its spring and the forward end of lever 200 will be lifted to close the circuit breaker.

Provision is made to limit clutch 464 to a single cycle of operation. To this end, detent 487 is provided with an extension 492, the free end of which is provided with a cam face 492'. When detent 487 is disengaged, the free end of arm 492 is moved downwardly, thus bringing the cam face 492' into position to be engaged by a pin 493 mounted on the driven member of the clutch 464. As clutch 464 approaches its full cycle position, pin 493 will contact cam face 492' raising arm 492 and thus moving detent 487 into position where it will engage the pawl of clutch 464 and disconnect the drive when the clutch reaches full cycle position. As detent 487 is fast on shaft 486, the shaft will be rocked clockwise carrying arm 485 with it and moving slide 480 to the rear. The pin 493 of clutch 464 will pass under the cam face 492' providing sufficient movement to bring the shoulder 480' of the slide 480 to the rear of the restraining arm of latch 482 which will be urged into latching position by spring 483. The slide 480 will then be urged forward by its spring into contact with the latch 482 and the arm 492 moved slightly downward (Fig. 5). The latch 482 operates as above described only if the clear key 466 has been released before the completion of the cycle. If the key 466 has been released, the ear 482' abutting the end of setting slide 478 will move said slide to the right to its unset position. However, should the clear key be held depressed, the setting slide will be held to the left and by contact with ear 482' hold the latch in rocked clockwise position, from the position shown in Fig. 4, out of the path of movement of the shoulder 480' of slide 480. In this instance, a latch lever 494 having common pivotal mounting with latch 482 will be urged clockwise by spring connection with latch 482, thus positioning it in the path of movement of the shoulder of slide 480, thereby preventing forward movement of the slide. When key 466 is released, latch 482 will then be free to be moved counterclockwise by spring 483 and return slide 478 to normal. At latch 482 is moved, it will, by contact with latch 494, move said latch out of engagement with slide 480 and itself be moved into latching position.

Clutch 464 furnishes the drive for the clearout operation by an eccentric cam 495 mounted on the driven member thereof. The eccentric cam is adapted to impart a reciprocatory movement to a link 496 (Fig. 5) which is attached at its forward end to a crank arm 497 which is fixed on the shaft 484 which extends across the machine. Thus, when clutch 464 is operated, shaft 484 is rocked clockwise (Fig. 5), counterclockwise (Fig. 1) during the first half of the cycle to rock clearout bail 515 to depress zero keys 19, and during the second half of the cycle shaft 484 will be rocked back to normal thereby releasing bail 515 as follows:

The bail 515 is provided at its rightmost end with a depending arm 517 (Figs. 1 and 2) adjacent the inner wall of the right hand side frame. A push link 518 is attached to the arm 517 and

extends rearwardly and in sliding contact with the inner wall of said frame. Mounted on the rear end of link 518 is a stud 519 extending through a horizontally disposed slot in the side frame and provided with an enlarged head which prevents lateral displacement of the link 518. Ball 515 is normally maintained in unrocked position by a spring 520 attached to the lower end of arm 517, thereby holding link 518 toward the rear and stud 519 normally at the rear of its slot. Shaft 484 (Fig. 1) extends through the right hand side frame externally thereof and is provided with an end portion, the sides of which are flattened to provide rotary drive to a member 521 slidably mounted thereon. Member 521 is provided with an upstanding lug 521' normally positioned to the right and rear of the head of stud 519. Clearout slide 478 (Figs. 1 and 4) extends to the right beyond the side frame and terminates in a rearward projection provided with a slot which engages a rim of member 521. Therefore, when key 466 is depressed and slide 478 moved to the left from the position shown in Fig. 4, the lug 521' of the member 521 will be brought into the plane of the head of stud 519. As shaft 484 is rocked counterclockwise (Fig. 1) by action of clearout clutch 464, member 521 will be accordingly rocked and lug 521' will contact the head of stud 519 thereby moving link 518 to rock bail 515 and release any set keys 18. In the second half of the cycle of clutch 464, member 521 will be returned in clockwise direction thereby releasing bail 515 which will be restored by spring 520.

From the foregoing, it will be seen that the motor operated clearout bail 515 will be invariably restored from its key depressing position regardless of the continued depression of operating key 466.

Selective keyboard non-clear

It is possible to set a constant value in the keys 18 by manually holding each of the zero keys 19 of the selected columns depressed during the setting operation as disclosed in Patent No. 1,750,565. This, however, entails awkward and at times plural operation. To obviate these disadvantages of the motor-operated clearout means herein described, the present invention as disclosed provides a latching means which will be effective to hold bail 515 in rocked position as long as the operating clearout key 466 is held manually depressed.

The latch 522 (Figs. 1, 2 and 4) is pivotally mounted on a stud 523 on the right hand side frame and is spring biased for engagement with a rightwardly extending lug 517' of arm 517 on bail 515. Latch 522 is normally held from engagement with lug 517' by a pin 524 which underlies an arm 522' integral with said latch as shown in Fig. 1. Pin 524 is located at the end of the stem of operating key 466 and also provides the pivotal connection for arm 470. Upon depression of key 466, pin 524 will be lowered to the position shown by the dot-dash lines (Fig. 2) and thus permit latch 522 to engage lug 517' before bail 515 is rocked. Therefore when bail 515 is rocked, lug 517' will be moved to the position where it will be engaged by the effective end of latch 522 as shown in Fig. 2. It will be seen that bail 515 will be held in rocked position against the tension of spring 520 as long as key 466 is held depressed thereby holding the zero keys 19 in latched position to permit the setting of a constant value in keys 18. Upon release of key 466,

its restoring spring 466' will overcome the spring of latch 522 thereby releasing bail 515.

Although I have shown and described the invention in conjunction with a particular motor drive for the clearout devices, it will be obvious that other motor operated driving means may be employed without departing from the scope of the invention.

I claim:

- 10 1. In a motor operated calculating machine having value entering mechanism including a plurality of columns of depressible value keys; each of said columns including digital value keys and a zero key, and latching means for each of said columns for holding any one of said keys of the related column in depressed position and movable upon depression of any one of said keys to release any latched key of the same column; the combination of a bail movable to simultaneously depress all of said zero keys, means driven by the motor for moving and thereafter releasing said bail, spring means for restoring said bail from key depressing position, an operating key for initiating operation of said driving means, and normally disabled latching means controlled by said operating key to hold said bail in key depressing position whereby depression of digital value keys will be ineffective to release the related zero keys.
- 15 2. In a motor operated calculating machine having value entering mechanism including a plurality of columns of depressible value keys, each of said columns including digital value keys and a zero key, and latching means for each of said columns for holding any one of said keys of the related column in depressed position and movable upon depression of any one of said keys to release any latched key of the same column; the combination of a bail movable to simultaneously depress all of said zero keys, means driven by the motor for moving and thereafter releasing said bail, spring means for restoring said bail from key depressing position, a depressible operating key for initiating operation of said driving means, and normally disabled latching means controlled by said operating key to hold said bail in key depressing position whereby depression of digital value keys will be ineffective to release the related zero keys.
- 20 3. The invention according to claim 2 characterized by the provision of a spring for urging the latch means for engagement with the bail, and wherein the enabling and disabling means comprises a contact member on the operating key for engaging said latching means, thereby moving and maintaining said latching means from engagement with said bail upon retraction of said operating key and permitting the engagement of said latching means with said bail upon depression of said operating key.
- 25 4. In a motor operated calculating machine having value entering mechanism including a plurality of columns of depressible digital value keys, latching means for each of said columns for holding any one of said keys of the related column in depressed position and movable upon depression of any one of said keys to release any latched key of the same column, and an individual releasing element for each of said columns movable to effect the key releasing movement of the related latching means and thereafter adapted to be held in inoperative position by said related latching means and to be released therefrom upon depression of a key in the related col-

umn; the combination of a bail operable to simultaneously move all of said key releasing elements to inoperative latched position, means driven by the motor for operating and thereafter releasing said bail, spring means for restoring said bail from operated position, an operating key for initiating operation of said driving means, and normally disabled latching means controlled by said operating key to hold said bail in operated position whereby depression of digital value keys will be ineffective to release the related key releasing elements.
